DESIGN FOR A GLASS JAR

Harry C. Gessler, Brooklyn, N. Y., assignor to
Medco Products, Inc., North Bergen, N. J., a
corporation of New Jersey

Application July 10, 1946, Serial No. 131,441

Term of patent 14 years

(Cl. D58—25)

To all whom it may concern:

Be it known that I, Harry C. Gessler, a citizen of the United States, and resident of Brooklyn, in the county of Kings and State of New York, have invented a new, original, and ornamental Design for a Glass Jar, of which the following is a specification, reference being had to the accompanying drawing, forming a part thereof, and of which Figure 1 is a view of a glass jar, showing my new design; Fig. 2 is a sectional view thereof taken on line 2—2 of Fig. 1; and Fig. 3 is a sectional view taken on line 3—3 of Fig. 2.

I claim:

The ornamental design for a glass jar, substantially as shown.
